UNITED STATES PATENT OFFICE

ANDREW THOMA, OF CAMBRIDGE, MASSACHUSETTS, ASSIGNOR TO NORTH AMERICAN CHEMICAL COMPANY, OF BOSTON, MASSACHUSETTS, A CORPORATION OF MASSACHUSETTS

METHOD OF FILLING SHOES

Application filed January 6, 1928. Serial No. 245,001.

In the use of certain kinds of filler in the shoe bottom there has been found to be a tendency for the same to mold in the shoe-bottom in damp weather or under certain 5 temperature and humid conditions. Such filler is set forth in my method application Ser. No. 210,558 and article application Ser. No. 211,157. The present method aims to render this unfortunate result impossible. To 10 this end I may provide substantially the same filler ingredients as set forth in the aforesaid applications, the principal difference being that I eliminate or expel the volatile constituents from within the porous body material at some time before the filler gets into 15 the shoe-bottom. To this end I preferably mix the comminuted body material with an enveloping gelatinous paste or other crust forming medium so as thoroughly to coat 20 each granule or particle of the body material with a thin film thereof, and then by heat or other means of evaporation I drive off all the evaporable constituent from said coating and also from within the body material granule 25 in case any of the volatile element should have penetrated thereinto. In other words I thus maintain the dry granular condition, but coated and protected by an impervious film or skin like a jacket or armor. This 30 removes the element which has heretofore caused the molding above mentioned.

In my previous Patent No. 1,032,312, dated July 9, 1912, I combined pasty ingredients with wax tailings and the like as a binder 35 but not so as to form a skin and provide against the molding, or so as to accomplish any of the results of the present invention. In the disclosure of said patent there was no 40 impervious skin, no barrier in the sense of the present invention, the cork was not maintained with its original light weight, and a subsequent cooking process was necessary for developing the paste, besides many other radical differences which it is unnecessary 45 here to point out.

With my filler as first above explained when the filling operator is ready to fill his shoe bottom he releases or softens this crusted 50 coating by heat, moisture, steam or whatever quickening process the particular kind of

coating calls for so as to render the filler readily spreadable in the shoe-bottom. The encrusting coating may be sufficient in amount and character to constitute the binder itself or preferably it simply holds the 55 filler particles protected as stated but still discreet, and in such case the binder is mainly separate in the form of wax tailings or other waxy or sticky material of well known character. 60

In the drawing, in which I have graphically illustrated my method,

Fig. 1 is a conventional view broken away or sectioned of a mixer; and

Fig. 2 is a cross sectional enlarged detail 65 of a chunk-like piece of filler constructed for carrying out my method.

It will be understood that the filler may be of any of the usual plastic varieties, many of which are disclosed in my filler patents 70 and also in my copending filler applications. It is sufficient to refer to the above two mentioned copending applications. The comminuted filler material, as for instance ground cork, is thrown into a mixer 1 with a 75 quantity of preferably thick gelatinous, jelly-like coating material such as apparatus, gelatin, glue, paste, or any pasty materials like starch, dextrine, flour, magnesia compounds, shellac, or the long list of resinous substances, and thoroughly agitated or mixed preferably in the presence of heat. The object is to thoroughly coat each particle of the body material with as thin but complete a coating skin as possible while at the 80 same time driving off by means of the heat and the agitation all volatile penetrative substances present, thereby leaving the body material thoroughly coated with an impervious covering and in as light weight a condition as possible. Then this mass of body material composed of the individually coated, 85 relatively discreet granules or particles, is thoroughly mixed with any suitable binder, as for example melted wax tailings, or any other of the large variety of binders. The binder material is poured into the mass, in the mixer 1 and thoroughly mixed. It is unnecessary to explain this step any farther 90 as it is substantially the same as has hereto- 95

fore been long practiced in making fillers. Of course if a binder is used which does not require heat, the mixer is not heated. The mixer is first heated as first above explained, simply to hasten the evaporation of the volatile portion of the coating element as well as to drive out the moisture, if any, from within the particles and leave them completely armored or protected with a skin. By impervious I mean that it will not admit penetration or absorption of the external binder element whatever it may be in the particular filler. In the mixer in Fig. 1 I have indicated at 2 the mass of particles being mixed and in Fig. 2 I show the cork or other comminuted body elements 3 coated with a protector 4 and, in case said protector is not itself a binder or is considered insufficient, a separate or additional binder 5 is employed.

The result is that the filler material has no tendency to mold or deteriorate as an article of manufacture, but is ready, and maintained in proper condition, at all times by this process. When the shoe is to be filled the operator quickens the filler by such suitable means as is called for by the particular combination of elements present. For instance if the binder be wax tailings and the coating is a varnish or covering of rosin or other resinous material, the quickening agency is simply heat. On the other hand if the coating is an encrusting of apparatus, for example, the filler is subjected to steam. This is maintained just sufficiently to soften the mass of filler and render it spreadable, whereupon it is at once spread in the shoe-bottom. In case the covering material is disrupted by pressure or in any other way and removed from its protecting relation to the body particles, and in case the latter are absorbent, the result then is that a portion of the binder material is at once absorbed thereby. For instance if the binder material be wax tailings, an appreciable portion of said wax tailings are sucked in or absorbed by the ground cork so as to stiffen the laid filler as soon as the wax tailings have served their function of rendering the filler spreadable. The result is that the laid filler now becomes relatively stiff and yet permanently resilient, which two results are essential in an ideal filler layer.

What I claim and desire to secure by Letters Patent is

The method of making spreadable shoe bottom filler which comprises coating the individual particles of comminuted, fibrous, absorbent body material with a fluid paste made of a suitable film-forming substance and an evaporable liquid, then drying the coated particles and driving off whatever evaporable liquid may be present both in the coating and in the coated particles, leaving each particle enclosed by a dry, protective film adapted to prevent penetration and absorption by the particles of external binder and of external

moisture, and adapted to be disrupted in use, and then mixing the dry film-coated particles with a sticky binder to form a homogeneous filler composition.

Signed by me at Cambridge, Mass. this 70
fifth day of January 1928.
